UNITED STATES PATENT OFFICE.

HARRY D. LATHROP, OF CHICAGO, ILLINOIS.

CAN INVERTING MEANS.

Original application filed November 24, 1920, Serial No. 426,258. Divided and this application filed August 29, 1921. Serial No. 496,419.

To all whom it may concern:

Be it known that I, HARRY D. LATHROP, a citizen of the United States, and a resident of the city of Chicago, county of Cook and State of Illinois, have invented certain new and useful Improvements in Can-Inverting Means, of which the following is a specification.

My invention relates to new and useful improvements in can inverting means, and more particularly a can inverting mechanism used in conjunction with a can washing machine, and has for its object the provision of a device of this class which is made up of few parts, which is economical to manufacture, and at the same time is efficient and durable.

Other objects will appear hereinafter.

This case is a division of my application filed November 24, 1920, Serial No. 426,258.

The invention consists in the combinations and arrangements of parts hereinafter described and claimed.

The invention will be best understood by reference to the accompanying drawings forming a part of this specification, and in which,

Fig. 1 is a fragmentary side elevation of my invention.

Fig. 2 is a top plan view thereof, and Fig. 3 is a vertical section taken on line 3—3 of Fig. 2.

This application is directed to the can inverting means used in conjunction with my improved can washing machine, which is fully disclosed in the parent case above identified. The frame 10 of the can washing machine is provided with a slideway 11 for the cans, which comprises a pair of angle irons 12 spaced apart in suitable position to support the cans 13 of the ordinary type used for milk or cream, and angle irons 14 are placed a short distance above the angle irons 12 for holding the cans 13 from tipping out of their upright position.

The means for advancing the cans along the slideway comprises a bar 17 which is slidable longitudinally of the machine, and is also adapted to be rocked. The slide bar 17 is provided with a plurality of spaced arms 18 for engaging the can successively and moving them along said slideway, in

accordance with the arrangement of cleaning devices located along the machine, as fully disclosed in the above identified parent case. When a plurality of cans are in position on the slideway 11 and it is desired to give the cans a forward movement, the bar 17 is given a partial rotation so as to extend the arms 18 laterally of the cans 13, and the bar and cans are moved forward, giving the cans a step-by-step sliding movement along the slideway 11, delivering a can at a time to the can inverting means for turning the can from inverted to upright position, as is best shown in Fig. 3. The numerals 19 and 20 denote the trackway and receiving platform, respectively, of the can-cover delivery means, disclosed in my above identified case.

The means for turning the cans from their inverted position on the slideway into an upright position upon a platform 21 at the delivery end of the machine, and for holding them firmly in said upright position at this point forms the subject matter of this invention. Said means comprises a rounded turning member in the form of a pair of superposed metal straps 22 which are secured at one end to the frame work 10, opposite the end of the slideway. As is best shown in Fig. 3, the straps or bars 22 are curved downwardly away from the slideway, and then extend forwardly and upwardly, being turned downwardly again and secured at their lower ends to the frame work. By reason of the depression provided by the downwardly bent portion of the bars 22, the cans 13 are adapted to tip forwardly as they slide from the end of the slideway, the side of the can being brought into engagement with the rounded and elevated portion of the bar 22. I have found in practice that when a can is brought into engagement with my improved turning device in the course of a normal forward movement of the can under the influence of can forwarding means, disclosed in the parent case above identified, the force of the forward movement of the can and the over-balanced weight of the can in tipping serves to turn the can into upright position. For receiving the can 13 and for holding it against lateral tipping, thereby

completing the turning movement of the can, I have provided a cross bar 23 which is fixedly mounted at the upper ends of a pair of arms 24 pivotally mounted upon the frame work 10 by means of pivot pins 25. The lower end of the arms 24 are connected by a cross bar 26 which is of such a weight as to hold the upper cross bar 23 normally in position shown in Fig. 3. When the can 10 is brought in contact with the cross bar 23, the cross bar is moved forwardly, as is shown in dotted lines in Fig. 3, serving to bring the lower cross bar 26 into contact with a stop 27 mounted upon the frame 10, 15 which stop serves to limit the forward movement of the upper cross bar 23. As is best shown in Fig. 2, the central portion of the cross bar 23 is curved forwardly, to conform substantially to the curvature of the side 20 of the can, so as to hold the can from tipping laterally. By the time that a can is delivered in upright position upon the platform 21, as above described, two or three covers will be waiting on the adjacent platform 25 at the delivery end of the slideway 19 for covers. By this construction the can is properly inverted and is firmly held in upright position, at the delivery end of the can washing machine, permitting the cover, 30 delivered on platform 20, to be immediately placed on the can, thus enabling the cans and covers to be delivered in a very expeditious manner.

While I have illustrated and described the 35 preferred form of construction for carrying my invention into effect, this is capable of variation and modification without departing from the spirit of the invention. I, therefore, do not wish to be limited to the 40 precise details of the construction set forth, but desire to avail myself of such variations and modifications as come within the scope of the appended claims.

Having described my invention, what I 45 claim as new and desire to secure by Letters Patent, is:—

1. A can inverting means associated with the slideway of a can washing machine, said inverting means comprising a metallic strap 50 projecting forwardly from the center of the slideway, being bent upwardly and then downwardly adjacent the end of the slideway for permitting a can on the slideway to tip forwardly and to turn over said strap 55 into upright position, and means for engaging the lower portion of the can to complete the turning movement and to hold the can against tipping.

2. A can inverting means associated with 60 the slideway of a can washing machine, said inverting means comprising a member mounted near the end of the slideway in slightly elevated position with respect thereto, adapted by engagement with the side of 65 the can in its forward movement to give the

can a turning movement; and a cross bar adapted by engagement with the can near its lower portion to complete the turning movement and to hold the can against tipping from upright position.

3. A can inverting means associated with the slideway of a can washing machine, said inverting means comprising a strap mounted near the end of the slideway, curved upward and then downward, adapted by engagement with the side of the can in its forward movement to give the can a turning movement; and a cross bar movably mounted opposite the end of the slideway adapted, by engagement with the can near its lower portion, to complete the turning movement of the can and to hold the can against tipping from assumed upright position.

4. A can inverting means associated with the slideway of a can washing machine, said inverting means comprising a curved member mounted near the end of the slideway in slightly elevated position with respect thereto, adapted by engagement with the side of the can in its forward movement to give the can a turning movement and a cross bar curved to conform substantially to the shape of the can adapted by engagement with the can from said curved member to complete the turning movement and to hold the can against tipping laterally.

5. A can inverting means associated with the slideway of a can washing machine, said inverting means comprising a curved strap mounted at center of said slideway near the end thereof, adapted by engagement with the side of the can in its forward movement to give the can a turning movement; arms pivotally mounted opposite the end of the slideway and movable toward and from the end of the slideway; a cross bar carried by said arms, adapted by engagement with the can near its lower portion to complete the turning movement of the can; and stop means for limiting the forward swing of said arms.

6. A can inverting means associated with the slideway of a can washing machine, said inverting means comprising means near the end of the slideway in slightly elevated position with respect thereto, adapted by engagement with the side of the can in its forward movement to give the can a turning movement; arms pivotally mounted opposite the end of the slideway and movable toward and from the end of the slideway; a cross bar carried by said arms, adapted by engagement with the can near its lower end to complete the turning movement of the can; means for holding said arms yieldingly in position; and stop means for limiting the forward swing of said arms.

7. A can inverting means provided in a washing machine at the end of the slideway, said inverting means comprising a curved strap fastened to the machine frame at the

end of the slideway and extending downward, then upward and again downward, adapted to turn the can in its forward movement; arms pivotally mounted at the 5 end of the slideway and movable toward and from the end of the slideway; a cross bar carried by said arms, adapted by the engagement with the can near its lower end to complete the turning movement of the can; 10 means for holding said arms yieldingly in

position; and stop means for limiting the forward swing of said arms and bar.

In testimony whereof I have signed my name to this specification in the presence of two subscribing witnesses.

HARRY D. LATHROP.
